GEORGE A. TURNER, OF STOCKTON, CALIFORNIA.

FUEL CONTROL FOR INTERNAL-COMBUSTION ENGINES.

1,261,740

Specification of Letters Patent.

Patented Apr. 2, 1913.

Application filed November 1, 1916. Serial No. 128,975.

To all whom it may concern:

Be it known that I, GEORGE A. TURNER, a citizen of the United States, residing at Stockton, in the county of San Joaquin, State of California, have invented certain new and useful Improvements in Fuel Controls for Internal-Combustion Engines; and I do declare the following to be a full, clear, and exact description of the same, reference being had to the accompanying drawings, and to the characters of reference marked thereon, which form a part of this application.

This invention relates to improvements in the control of the fuel supply connected with internal combustion engines of all types. There is a growing tendency by the users of such engines to adopt distillate or similar fuels as a most satisfactory fuel for use in engines of the type noted. The main drawback to the use of this fuel, however, is that it is a very hard fuel with which to start the engine, due to the fact that its combustion is much greater when it is heated or admitted into a heated engine. This difficulty can be overcome by having a supply of gasoline, or other more volatile oil, present in the carburetor of the engine when it is desired to start the same. The difficulty of doing this, however, has heretofore rendered the use of distillate somewhat unpopular. It is therefore the aim of my invention to provide an automatic means for supplying either gasoline, a mixture of gasoline and distillate, or distillate itself, directly to the carburetor.

My invention therefore embodies a gasoline supply and a distillate supply leading to a common control valve with a single pipe leading from the valve to the carburetor. The valve itself is so constructed that it can be operated to deliver to the single pipe either the gasoline or mixture of gasoline and distillate, or the distillate alone, and, in addition to this, can shut off both. The advantages of this shutting off of both are many, the principal one being that it prevents a waste of the fuel out of the carburetor by evaporation or leakage. A very large per cent. of all carburetors leak when left standing for a period of time, but by complete shutting off of the fuel supply, this is obviated. Also when an engine is stopped, it is usually very hot and the carburetor being immediately adjacent the engine, the evaporation caused by the heat

is very great with the resultant loss of a large percentage of the fuel.

My improved valve will be automatically controlled with the throttle lever of the carburetor. As the car is brought to a stop, the throttle lever is moved to retard the fuel supply, and, with this movement the control valve noted above is operated first to shut off the distillate supply gradually and then substitute therefor the gasoline supply so that when the car comes to a stop the gasoline supply will be in direct communication with the carburetor so that when the car is ready to start again, the gasoline will be present for starting purposes. Then as the throttle is advanced for speeding up the engine, the gasoline supply will be gradually cut off and the distillate supply substituted therefor.

I also aim to provide a structure which permits of the acceleration of the speed of the engine independently of the valve control means when the same becomes necessary.

As a still further advantage of my improved control means I provide a lock carried by the valve so that it can be locked in closed position which will prevent the theft or unauthorized use of the car. Also there are a great many other advantages of my improved structure which will be obvious as the description of the same is proceeded with.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Figure 1 is a plan view of the steering wheel of a motor vehicle showing the throttle lever thereon for the purpose of illustrating the different positions of the same with respect to the control valve.

Fig. 2 is a plan view of the control valve broken out and in section to show the interior structure thereof. The relative size of this valve is here shown as somewhat larger than it would probably be in actual practice in order that the different parts

may be boldly brought out. The valve in the position shown in this figure is that which it assumes when communication between the gasoline and distillate pipes and the carbureter pipe is closed completely.

Fig. 3 is a sectional view of the valve showing it in that position which it will assume when the gasoline pipe and the carbureter pipe are in communication with each other.

Fig. 4 is a similar view showing the gasoline and distillate pipes both in communication with the carbureter pipe.

Fig. 5 is another similar view wherein the distillate pipe alone is in communication with the carbureter pipe.

Referring now more particularly to the characters of reference on the drawings, the numeral 1 designates a pipe which would be connected with the gasoline supply means which could be either an independent receptacle or a divisional part of the main fuel tank. The numeral 2 designates the distillate supply pipe. These pipes 1 and 2 communicate with the valve casing 3 at points closely adjacent one another for a purpose as will presently appear. The carbureter pipe 4 leads from the opposite side of the casing 3. The valve disk 5 rotates within the casing 3 and is provided with a port 6 of substantially the same diameter as the pipes 1 and 2 arranged to register with either of the pipes 1 or 2 or partly with each. This port 6 enlarges at its opposite end as at 7 where it is of such diameter as to register with the pipe 4 whenever the portion 6 thereof is in register with either of the pipes 1 or 2 or partly with each. By means of this structure therefore the pipe 4 may be put into communication with the pipe 1 alone, partly with each of the pipes 1 and 2, or with the pipe 2, merely by rotating the disk 5.

This rotation of the disk 5 is accomplished by means of the valve lever 8 which connects with the disk 5 in the usual manner. This lever 8 has a slotted end 9 which fits over the throttle control rod 10 of the engine. This throttle rod 10 is provided with two spaced threaded portions 11 mounted on which are adjustment nuts 12. Spiral springs 13 are disposed around the rod 10 and are interposed between the nuts 12 and small follower heads 14 which impinge against the slotted end 9 of the lever 8. The tension of the springs 13 is controlled by the nuts 12 and is such that under the ordinary movement of the rod 10 the lever 8 will be moved to turn the disk 5.

Referring now to Fig. 1, the numeral 15 designates the throttle lever which controls the movement of the rod 10 and this moves over the usual quadrant 16. In providing my improved invention, this throttle lever is provided with four designating points

"a", "b", "c" and "d". When the throttle lever 15 is at the point "a", the rod 10 is in that position which holds the disk 5 in the position shown in Fig. 1, which shuts off all of the fuel from the carbureter. When the lever 15 is at the position "b", the disk 5 is in that position shown in Fig. 3 where the gasoline supply is connected up with the carbureter. The position "c" places the disk 5 in that position shown in Fig. 4 where a mixture of gasoline and distillate is admitted to the carbureter. The position "d" places the disk 5 in the position shown in Fig. 5 wherein distillate alone is being admitted to the carbureter. The tension of the springs 13 is sufficient to move the lever 8 so that the disk 5 will move to all these various positions. If, however, it is desired to still further accelerate the speed of the motor, the rod 10 can be forced still further, this being permitted of by reason of the fact that the springs 13 will then give under the pressure against the lever 8. The disk 5 of course is provided with the usual valve stops for preventing this further movement under these conditions.

Assuming now that the engine has been stopped for a period of time, the lever 15 will be at the position "a" and the control valve consequently completely closed. The operator of the engine desires to start same so he moves the lever 15 to the position "b". This opens communication between the pipe 1 and the pipe 4 and admits pure gasoline to the carbureter. As is well known, this is a fuel with which it is easy to start the engine. The engine being started and gradually accelerated, the lever 15 is moved gradually from the point "b" to the point "c". This opens communication from the pipe 2 to the pipe 4 so that distillate is added to the gasoline, and this is continued until the point "c" is reached, at which point an equal amount of gasoline and distillate is used. The continued advancement of the lever 15 from the point "c" to the point "d" gradually diminishes the gasoline supply and increases the distillate supply until the point "d" is reached, at which point clear distillate is admitted to the carbureter. By this time the engine is sufficiently under way to properly handle the distillate as its fuel. The advantages of this fuel are many, among which is its lesser cost and its better volatile qualities when admitted to a warm engine.

During the ordinary daily operation of the engine when the engine is brought to a stop, the throttle lever 15 is of course gradually retarded. This first shuts off the distillate and admits gasoline and distillate and then finally shuts off the distillate and admits gasoline alone. During this daily operation the lever 15 would not be retarded any further than the point "b", which

would keep a continuous supply of the gasoline in the carbureter. The position "a" would be used when the engine was stopped for a definite period so that leakage of the carbureter and evaporation of the fuel therefrom could be avoided.

When the engine is to be stopped for a definite period and a theft or unauthorized use of the vehicle to which it is attached is to be prevented the disk 5 is turned to full closed position. When in this position a small recess 17 therein is in register with the lock bolt 18 on a suitable key lock mechanism 19. The lock 19 is then operated with this key to bring the bolt 18 into the recess 17 which prevents the movement of the disk 5 until unlocked again. The result of this is obvious.

Having set forth now in detail my improved invention, the manifold advantages thereof will be readily apparent to those skilled in the use of internal combustion engines, and, while a few of the many advantages are set forth in the preamble to this specification, still there are a great many others. Probably the greatest of these is the fact that the entire structure is absolutely automatic and when once installed needs no particular attention other than the ordinary operation of the engine. The throttle lever is always naturally retarded to stop or start the engine and gradually advanced to accelerate the engine. With this operation the fuel is controlled automatically in the carbureter, which is the most advantageous for the purposes noted. The use of the double fuel has often been advocated but never been put into practice due to the fact that there has been heretofore no way of automatically controlling the same which is the only practical way to handle it.

From the foregoing description it will be readily seen that I have produced such a device as substantially fulfills the object of the invention as set forth herein.

While this specification sets forth in detail the present and preferred construction of the device, still in practice such deviations from such detail may be resorted to as do not form a departure from the spirit of the invention as defined by the appended claims.

Having thus described my invention what I claim as new and useful and desire to secure by Letters Patent is:

1. The combination with an engine having a carbureter and a throttle lever for controlling the quantity of combustible mixture drawn by the engine from the carbureter, of a means for varying the grade of the fuel admitted to the carbureter in direct relation to the quantity of the combustible mixture

drawn therefrom, such means including a valve having inlets for admitting different grades of fuel and a single outlet, the valve having a port arranged to place either or 65 all of the inlets into communication with the outlet, the throttle lever being operatively connected with the valve, whereby when the lever is moved to increase the quantity of combustible material drawn from the carbureter it will first place the outlet in communication with one inlet, then with two, and then with another, so that the grade of the fuel admitted into the carbureter will be gradually altered in direct relation to the 75 quantity of the combustible mixture drawn from the carbureter.

2. A fuel control for an internal combustion engine, comprising a valve casing having two inlets for the purpose of admitting 80 two different fuels to the casing, a single outlet from the casing arranged to lead to the carbureter of the engine, a disk turnable within the casing and having a port for opening communication between either or 85 both of said inlets and said outlet, a throttle lever for controlling the quantity of the combustible mixture drawn from the carbureter into the engine, a means interposed between said throttle lever and the disk 90 whereby, when the throttle lever is moved to increase or diminish the quantity of the combustible material drawn from the carbureter into the engine, the outlet from said casing will be consecutively placed in connection first with one inlet, then with both and then with the other whereby the grade 95 of the fuel admitted to the outlet will be regulated in direct relation to the amount of combustible mixture drawn from the carbureter into the engine.

3. The combination with a carbureter having a fuel inlet arranged for communication with supply means for different grades of fuel, of means controlled by the throttle 105 lever of the carbureter for gradually altering the grade of the fuel admitted to the carbureter in direct relation to the quantity of combustible mixture drawn from the carbureter.

4. The combination with a carbureter fuel inlet pipe, of means operable by the throttle lever of the carbureter for controlling the grade of the fuel admitted into the inlet pipe in direct relation to the quantity of combustible mixture withdrawn from the carbureter, said control including means for completely closing the fuel inlet pipe when none of such mixture is being withdrawn from the carbureter.

In testimony whereof I affix my signature.
GEORGE A. TURNER.
